Inventor
Moses M. Downer

By Attorney

UNITED STATES PATENT OFFICE.

MOSES MOODY DOWNER, OF BRIDGEPORT, CONNECTICUT, ASSIGNOR TO LA RESISTA CORSET CO., OF BRIDGEPORT, CONNECTICUT, A CORPORATION OF CONNECTICUT.

CORSET.

Application filed November 25, 1922. Serial No. 603,158.

To all whom it may concern:

Be it known that I, MOSES MOODY DOWNER, a citizen of the United States, residing at the city of Bridgeport, in the county of 5 Fairfield and State of Connecticut, have invented certain new and useful Improvements in Corsets; and I do declare the following to be a full, clear, and exact description of the invention, such as will enable 10 others skilled in the art to which it appertains to make and use the same.

This invention relates to certain new and useful improvements in corsets, and the primary object thereof is to provide a corset 15 which has the hooks and also the eyes for the hooks mounted on sections that are flexibly connected to the vertical side front parts of the corset body, thereby to not only facilitate connection of the hooks and eyes, 20 but to also afford greater comfort to the wearer.

The invention further aims to provide hook and eye carrying sections which are reinforced by flexible means, such as woven 25 wire springs, or the like, the sections having the hooks and eyes secured in advance of the reinforcing means so that the pull or tension of the hooks and eyes will be rendered uniform, and at the same time the 30 strain on the elastic, which connects the reinforcing means and the hooks and eyes to the corset body, is uniformly distributed throughout the length of the elastic.

Still further, the invention aims to provide improved means for assembling the various parts to afford a durable and lasting structure.

The invention has still further and other objects which will be later set forth and 40 manifested in the course of the following description.

In the drawings:—

Figure 1, is a fragmentary elevation of one side of the corset,

45 Figure 2, is a section on line 2—2 of Figure 1.

Figure 3 is a front elevation of the corset.

In proceeding in accordance with the present invention, it will be understood that each 50 free side part of the corset is constructed alike, the drawings illustrating the part carrying the hooks. The side part 1, of the corset body is suitably secured to a section 2 of elastic, the elastic section extending throughout the length of the corset. The

hooks 3 are riveted at 4 to and along the outer side of a fabric strip 5. A suitable flexible stay, such for example as the woven wire spring 6 extends throughout the length of the corset and overlies the opposite or 60 inner side of the hook-carrying strip 5. Connecting strips 7 and 8 of similar construction have their side edges inturned and engage opposite sides of and embrace the hook-carrying strip 5; the flexible stay 6 and 65 the outer side of the elastic section 2, the inner side 9 of the elastic section over-lapping the flexible stay so as to cushion the latter. Lines of stitching 10 secure the connecting strips 7 and 8 to the hook-carrying 70 strip 5, while a similar line of stitching 11 secures the inturned or inner sides of the strips 7 and 8 to the elastic section 2. The lines of stitching 11 and 10 further form or define a pocket in which the flexible stay 75 is confined or housed.

From the foregoing it will be seen that the flexible front section carrying the hooks is not directly connected to the flexible woven wire stay, but is separately mounted 80 between the connecting strips 7 and 8, the latter also carrying the flexible stay 6. In this manner, the hooks and eyes (not shown) are not subject to distortion, but exert uniform tension on the elastic strip 2 and also 85 on the flexible stay 6, so that an evenly balanced structure results, which affords maximum comfort to the wearer, and increased longevity of the corset.

It will be further noted that the strips 7 and 8 and the inner side of the flexible strip 5, afford a pocket receiving the flexible stay.

What is claimed is:—

1. The hereindescribed improvement in the construction of the meeting front sections of a corset, including an elastic strip extending the full length of the corset and stitched along its inner side edge to the front body portion of each section to form a part thereof, a pair of opposed fabric 100 strips each stitched along their inner vertical side edges to the outer vertical side edge portion of each elastic strip, fastening means secured between each pair of strips along the outer vertical side edge portions thereof, 105 said pairs of strips being connected by intermediate lines of stitching, which latter form pockets adjacent to the outer vertical side edge of the elastic strips, and a stiffening stay in each pocket. 110

2. The herein described improvement in the construction of the meeting front sections of a corset, including an elastic strip extending the full length of the corset and 5 stitched along one side edge to the front body portion of each section to form a part thereof, a fabric strip stitched to the other edge of each of the elastic strips and formed with a vertical shirr pocket, the front side 10 edge of the fabric strip beyond the pocket being composed wholly of the fabric itself, stiffening means in each pocket, and fastening means secured to the front side edge of the fabric strip.
- 15 3. The herein described improvement in the construction of the meeting front sec-

tions of a corset, comprising an elastic strip extending the full length of each of said sections and stitched along its inner edge to the front body portion of each section, a 20 fabric strip stitched to the outer edge of each of said elastic strips and forming a part of the sections and provided with a vertical shirr pocket adjacent the elastic strip and having its front edge portion beyond said pocket composed wholly of the fabric itself, a stiffening stay housed within the pocket of each section, and clasp elements secured to each front edge portion. 25

In testimony whereof I affix my signature 30 hereto.

MOSES MOODY DOWNER.
